UNITED STATES PATENT OFFICE.

JOHN HENRY STRINGHAM, OF JERSEY CITY, NEW JERSEY, ASSIGNOR TO AMERICAN COMBUSTION COMPANY, OF JERSEY CITY, NEW JERSEY, A CORPORATION OF NEW JERSEY.

NEBULIZER OF LIQUIDS.

1,082,777.

Specification of Letters Patent. Patented Dec. 30, 1913.

Application filed February 5, 1908. Serial No. 414,407.

To all whom it may concern:

Be it known that I, JOHN HENRY STRINGHAM, a citizen of the United States of America, and a resident of Jersey City, New Jersey, have invented certain new and useful Improvements in Nebulizers of Liquids, the principles of which are set forth in the following specification and accompanying drawings, which disclose the form of the invention which I now consider to be the best of the various forms in which said principles may be embodied.

This invention relates to nebulizers of liquids, that is, apparatus for causing liquids, and particularly fuel-oils and gas oils, to assume the form of an extremely fine mist; and the invention particularly relates to nebulizers of the free centrifugal type hereinafter disclosed, wherein the centrifugal action is obtained, not by moving parts or by stationary baffles in the passage or by the impact of an elastic aeriform fluid, but by the direction of admission into the passage.

An important object attained by the invention is the ability to employ an auxiliary fluid or aeriform body, for certain useful purposes to be described, in such way as to avoid the impact or "hammering" action of the same upon the liquid to be nebulized.

Other objects and results to be hereinafter described are also obtained.

The results accomplished by the invention are various and important, and include in nebulizers of the centrifugal type of this invention, the property of regulation within wide limits of the amount used of the liquids to be nebulized, and while permitting such regulation, the ability to produce a fineness of oil nebulization never before attained, even by means of the invention of prior Patent No. 876,108 of which I was one of the joint inventors, particularly when there is employed, in coöperation with this invention, as is possible, the small dimensions of the apparatus of said patent. One of the other important results is the attainment, particularly advantageous in the use of the invention as an oil burner, of a supply of oxidizing fluid so thoroughly and intimately admixed with the extremely fine particles of oil nebulae, as to constitute a product of heavy oil possessing a wholly novel order of combustibility and explosiveness.

Of the drawings, which are three-quarter

scale, Figure 1 is an elevation of a complete apparatus, including the supply pipes and valves A and O at the left, and the globe G of the prior burner art at the right, the invention (shown in Fig. 1 particularly at S and V) being here adapted as a nebulizer for use as an oil burner; Fig. 2 is a central longitudinal section of the invention, shown in particular at the extreme right, (at S and V), and provided with a cooling fluid circulation apparatus U, the invention being here adapted, as by the provision of cooling means, for use as a nebulizer in a gas manufacturing apparatus; Figs. 3 and 4 are sections of the nebulizing plug V of Figs. 1 and 2 along the lines 3-3, and 4-4, respectively of Fig. 2; and Fig. 5 is an elevation of a nebulizing plug V like that of Figs. 1-4, except that it is provided with a plurality of inlets for each of the two sets of inlet means A^o and O^o of the invention.

The extreme right end of Fig. 2, showing the present invention adapted for use in a gas manufacturing apparatus, is a section of substantially the same apparatus (the support S and nebulizing plug V) as is shown in Fig. 1 between the valves A, O, and globe G, wherein the invention is shown adapted for use as an oil burner, the only difference between the two figures as to the support S being that its shoulder D (Fig. 1), D' (Fig. 2), and threaded part T (Fig. 1), and T' (Fig. 2) are reversed in the two cases; in Fig. 1 the part T being at the right to permit the attachment of globe G, and in Fig. 2 the same part T' being at the left to permit screwing into the cooling fluid circulator U.

The extreme compactness of the construction and arrangement of parts S and V can be seen in Figs. 1 and 2, these parts being the only essential parts of a burner except the supply pipes. The oil burner of Fig. 1 may be used without globe G if desired, and in that case the threads T of part S can engage directly in the wall of a combustion chamber in a case where the burner is not used outside of any such chamber.

In Fig. 1 the supply pipes A' and O' engage directly in the support S, but in Fig. 2 the pipes A^o and O^o are cast in one piece with a collar C. In Fig. 2 the pipes A^o and O^o, which are the ones engaging directly in the support S, extend through the interior of the cooling fluid circulator U

- and through a second collar E to communicate with the pipes A' and O'. The collars C and E are provided with interlocking packing means, as shown, to prevent leakage of the water or of other cooling fluid. The water inlet is at B extending longitudinally through collars C and E, and the water outlet at a pipe F engaging in an elbow passage L in collar E.
- 10 The right hand ends of pipes A², O² of Fig. 2 (A' and O' of Fig. 1) are screwed into recesses A³, O³ (Fig. 2), and from these recesses extend passages A⁴, O⁴ in support S to its large central recess into which plug V is screwed by its threads R. Plug V has a passage Z and an outlet H (to be described in detail) through its head, which is hexagonal to readily permit screwing into support S. The left end of passage Z may be closed by plug K, and inlet passages A⁶ and O⁶ extend through the wall of plug V into passage Z, as shown, preferably in a plane at right angles to the axis of said passage, and one or preferably both entering passage Z eccentrically, as shown, and both preferably extending in the same clockwise or anti-clockwise direction with respect to the periphery of passage Z. The inlet passages are preferably so located at successive points along the axis of passage Z, that passage O⁶ is intermediate passage A⁶ and outlet H, i. e., so that passage A⁶ is slightly more remote from outlet H than is passage O⁶, passage A⁶ being therefore behind passage O⁶; but the two passages A⁶ and O⁶ are located as closely together as a sufficiency of projecting threads R on plug V will conveniently permit. The passage Z has a considerable length of interior surface, preferably substantially cylindrical, as shown, which is smooth and absolutely free and unobstructed, so as not to interfere with the whirling action which takes place therein, but on the other hand to permit the same for maximum nebulizing efficiency. When plug V is screwed into the large recess in support S, the projecting threads R divide said recess into two smaller chambers A⁵ and O⁵, and the proportions are such that when the closing plug K strikes the left end of the chamber A, as shown, the inlet passages A⁶, O⁶ register and are in communication with the separate chambers A⁵, O⁵. A copper washer W is preferably interposed between the right end of support S and the hexagon head of plug V.
- In construction the outer surface of part V is turned down to the proper dimensions for thread R and for the proper length of passages A⁶, O⁶, and then the threads R are cut. Passage O⁶ may be embodied in any desired manner in the structure consisting of the parts V and K or any equivalent structure, provided that it is not so directed into passage Z as to interfere with the whirling

action of the liquid to be nebulized. The cylindrical passage Z is smoothly drilled out to a proper distance for obtaining the desired length of outlet H, leaving the impression of the conical shape of the drill at the right, and then the outlet H is drilled from the outside, concentric with the axis of passage Z; passages A⁶, O⁶ being drilled as shown in Figs. 3 and 4. The left end of the interior passage Z is threaded to receive plug K, which, on final assembly of plug V, is screwed therein to close the end of passage Z, but not sufficiently far to block inlet passage A⁶, in a case where, as shown, passage A⁶ is not formed through plug K, as it may be. Especial pains are to be taken to make the surface of passage Z as smooth as possible, in order not to retain any obstruction which might interfere with whirling action. In support S the passages A⁴, O⁴ are drilled by a tool entering through the mouth of the large recess which is subsequently operatively divided into chambers A⁵, O⁵ by the insertion of plug V. The total area of both inlet means A⁶ and O⁶ is greater than that of outlet H.

The nebulizing action is believed to be as follows, the liquid to be nebulized, particularly crude petroleum or gas-oil, entering passage Z through inlet O⁶, and an auxiliary fluid, preferably aeriform and elastic such as steam, or compressed air or gas, entering passage Z through inlet A⁶. If the dimensions of oil inlet O⁶ are not suitable as in said patent, to cause a sufficiently high speed of the admitted oil, and if the dimensions of the other passages are not cooperatively suitable, to produce such a whirling film or skin of oil on the interior wall of passage Z as will cause perfect nebulization, then the auxiliary fluid, admitted into passage Z so as to whirl therein, and preferably in the same direction as the whirling oil film, but between it and the axis of passage Z, and expanding slightly, but only slightly in said confined passage in the same direction, causes an acceleration of the whirling action of the oil film in passage Z such that upon exit from outlet H the oil is broken up, by means of the operation of the apparatus, into extremely fine nebulæ. The shortness of passage Z, and particularly a short distance between passages A⁶, O⁶, permits a maximum whirling effect of the auxiliary fluid upon the oil by providing work for the auxiliary fluid as soon as it is admitted into said passage; inasmuch as the oil film apparently spreads slightly back toward the air inlet A⁶. It is preferable to admit the auxiliary fluid at least some little distance behind the oil, as shown, in order to obtain a maximum whirling effect upon all the admitted oil, and to insure against too much air in the nebulized mixture outside of outlet H, particu-

larly in cases where, by faulty valve-adjustment, the pressure of the auxiliary fluid might be so great as compared with the oil pressure, as to choke back the oil, which 5 might the more readily occur if the auxiliary fluid inlet were not behind the oil inlet. The breaking up of the oil occurs instantly upon its whirling exit from outlet H, probably partly on account of the sudden 10 expansion of the elastic auxiliary fluid as it leaves passage H; and there is usually no intermediate formation, prior to nebulization, of a hollow whirling oil bubble, as in the invention of said patent, although there is a 15 whirling of the nebulous mass.

There is apparently no breaking up or mixture of the fluids in the passage Z. The most efficient operation of the centrifugal action would be prevented by any action of 20 impact upon the oil by the auxiliary fluid in passage Z, or by any interference by any means with the free whirling action of the oil film in passage Z; and for this reason 25 this invention provides means for using the auxiliary fluid in such way as not to permit any impact or hammering action in passage Z, but at the same time to utilize its whirling force to cause, or cause an acceleration 30 of, the centrifugal action of the oil; and this means consists in the formation of the passage Z with its cylindrical portion described, which is perfectly smooth and which has, in and of itself, no vanes, barriers, angles, 35 serrations, grooves, rifling, or baffles of any kind which might cause the auxiliary fluid to hammer the surface oil film or interrupt the free action of said whirling film. Attempts to obtain whirling action of the air 40 or steam blast and of the oil, by means such as helical serrations or rifling of the surface of the cylindrical passage, or of an interior stem, result in merely spraying the oil in comparatively large particles, and such means reduces the speed of rotatory flow 45 in the passage which I have found it apparently to be so necessary to retain and accelerate, and would interfere with the whirling action which occurs under the proper 50 conditions herein specified, within the smooth interior surface of the cylindrical portion of the passage Z of this invention. The importance of the lack of obstructions 55 in passage Z is so great, as I have found, compared with the matter of whether or not the auxiliary fluid inlets A^e are in the same clockwise direction as the oil inlets O^e, that when there are no obstructions, this invention is operative, (although not to an optimum degree), irrespective of the relative direction 60 of the two fluid inlets, and of the location of the auxiliary fluid inlet provided only that the latter, (in cases where the eccentricity of oil inlet O^e to passage Z is such as to produce sufficient centrifugal action of 65 the oil itself), is not directed substantially

parallel with the axis of passage Z. The oil inlet O^e is preferably located to the left of the right end of the cylindrical portion of the passage Z in order to permit the oil to spread out into as thin a film as possible 70 over the smooth surface of the passage.

The result of the action when both fluids emerge from outlet H, is a thorough impregnation of the nebulous mass of oil with the expanded auxiliary fluid, which is obviously 75 harmless in cases of gas production or enrichment, (when the auxiliary fluid may be the same as that which is being produced or enriched), and of vast value, in the case of an oil burner, in providing a concentrated 80 supply of oxygen.

In operation as an oil burner, air valve A (Fig. 1) is first opened slightly, just off its seat. (If the oil valve O were opened first, the combustion would not be so good and smoke would result.) Then the oil valve O is opened slightly just off its seat. The resulting nebulous mass is then lighted with a match or torch. To increase the heat of the flame, each valve may be alternately and gradually opened wider until a flame of the desired color and heat is obtained; i. e., first oil valve O is opened wider to furnish more fuel, and then sufficient air for complete combustion of the increased quantity of oil 95 in the produced nebulae is provided by further opening air valve A. The flame is hollow and conical and in a constant state of rapid whirling. The presence of too much oil in the nebulae is indicated by smoking, by 100 the redness of the flame, and by the centrifugal shooting off of minute rockets of oil-nebulae particles not burned in the main flame, but burning red in the atmosphere low in oxygen outside of the main flame. 105 By proper regulation of the oil and air valves, the heat of the flame can be increased from the lowest heat of a yellow flame, through the increasing heat of an increasingly white flame, to the blue, or hottest 110 flame of very great heat suitable for forges and similar uses.

The shape of the flame may be varied in different devices by varying the length of outlet passage H, a short length of which 115 produces a short fat flame, a greater length producing a longer, thinner flame.

The simultaneous issuance at the place where nebulization occurs, (i. e., the outer end of passage H) of both the oil and the 120 expanding steam or air, apparently results in surrounding each minute particle of the nebulous body of oil with an envelop of expanding aeriform fluid rich in oxygen, the innumerable extremely minute particles of 125 oil apparently being closely packed together except for the oxygen envelop of each one, which highly concentrated combustible mixture seems to account for the highly combustible character of the product.

When the apparatus is used as a burner in an atmosphere of air, cooling circulation means additional to the oil and air circulation is usually not needed, because the heat is localized away from the apparatus and toward the object to be heated, and because the base of the flame does not extend entirely back to the apparatus on account of the blast away from the apparatus which results from 10 the simultaneous exit from the same small outlet of both the oil and expanding air or steam.

When the apparatus is used for gas production or enrichment, the operator may 15 proceed as above described for the burner use, the proper valve adjustment being determined by considerations of the generator-temperature, and the quality and amount of oil-gas produced. The valves A, O of Fig. 1 are here screwed to the left ends of pipes A⁹, O⁹ of Fig. 2, when the cooling apparatus in Fig. 2 is employed, as for the gas-producing use. In this use, the continuous production 20 of suitable nebulæ generally requires the use of said cooling arrangement, because the apparatus must not be permitted to become so unduly heated as to carbonize the oil, and it would become so heated without said cooling means on account of its location in the 25 hot wall of, and projecting into, a hot retort or generator. The same applies to the case of a burner used with a closed apparatus, such as a furnace operated at high temperature.

35 Various oils may be used, either for oil-nebulæ burning or explosion, or for gas-production, including the lighter hydrocarbons such as gasoline and kerosene; but the invention is more particularly useful 40 with the heavier oils such as crude petroleum, gas-oils and liquid tar, which cannot be gasified without great heat unless first nebulized.

The invention is useful for any purpose 45 when a combustible or explosive mixture is required as for an oil or gas engine supply; and the invention is useful not only as a burner for various purposes, such as heating the boilers of steam locomotives and motor 50 cars, but as a means for furnishing to gas engines and gas-motor-cars an explosive mixture of air and of the gasified nebulæ of cheap crude petroleum; and other liquids than oil may be nebulized for any desired 55 purpose.

A gas engine or steam boiler may be started with the apparatus of this invention without the initial use of an auxiliary fluid, which can thereafter be supplied to the apparatus, as steam from the boiler heated by 60 an embodiment of the invention, or as air compressed by the gas engine operated by an embodiment of the invention. The efficiency of such starting operation is largely due to 65 the smooth unobstructed cylindrical surface

of the passage Z of this invention, in addition to the short length of that passage, although the efficiency is greatest when the oil inlet area is sufficiently small to cause very high whirling action of the oil when 70 thus used initially or otherwise without any auxiliary fluid.

The pressures used with each fluid may vary widely, (except that the pressure of the auxiliary fluid should not exceed that of the liquid to be nebulized), but thirty pounds each is optimum for the example shown, using gas-oil, and steam or compressed air. On account of the whirling function of the auxiliary fluid, when it is so admitted as to 80 so operate or coöperate, the dimensions of the different passages may be various, and need not be so small as to thereby obtain a sufficiently high admission speed and resulting suitable whirling action and nebulization; although the use of sufficiently small oil inlets to contribute to the effective speed of whirling action will contribute to the efficiency of the apparatus with respect to 85 fineness of produced oil nebulæ. When 90 there is combined with the invention of said patent, as by the use of such effectively small passages, the feature of this invention wherein the auxiliary fluid positively contributes to the centrifugal action, the resulting nebulæ are finer than can be obtained by the use of the invention of said patent alone. The device of the dimensions herein disclosed however, constitutes a marvelously 95 effective embodiment for all cases.

The use of the whirling auxiliary fluid in this invention, in addition to its other important functions, constitutes a feature of great value in apparatus of this open centrifugal type, in that it provides an efficient 100 means for regulating the amount of liquid which is nebulized. In said patent the preferred method of regulation consisted in providing a plurality of separately acting and controlled nebulizers, one or more of 105 which were to be entirely shut off when a smaller product of nebulization was required; (although another method was to vary the length of passage Z); and the variations accomplished by varying the amount 110 of oil supplied to the passage Z for a single nebulizer, caused an accompanying undesirable variation in fineness of the produced nebulæ, on account of the resulting variation in the centrifugal action due to 115 the variation in the speed of admission of the oil into the passage. In the present invention, however, the use of the auxiliary fluid in such way as to aid the whirling action of the oil, permits the variation within wide limits of the amount and pressure of the oil supply, without material alteration of the character of the produced nebulæ. The auxiliary fluid pressure may also be varied within wide limits, (except that its 120

pressure should not exceed that of the liquid to be nebulized) particularly when the whirling action of the oil due to the invention of said patent is employed, and indeed 5 in such case the auxiliary fluid pressure may be as low as will permit a proper supply of oxygen to the nebulized product. In all cases, in order to secure complete combustion, the area of the auxiliary fluid inlet 10 means is greater than that of the oil inlet means, as shown. In this invention the regulation is so perfect that there is no need of a plurality of nebulizers in any case for the purpose of regulation; although it may 15 sometimes be desirable to use a plurality for the purpose of obtaining flames of shapes or areas suitable for heating particular objects, or to obtain a very large flame to heat some object of large area, such as a steam boiler; 20 although the shape of a single flame may be modified as by varying the length of outlet H, as above explained. The regulation permitted by this invention is practically unlimited, such that a given device can efficiently 25 operate on from a fraction of a quart of oil per hour up to a plurality of barrels of oil per hour, with perfect nebulization for any degree of oil supply.

In departing from the dimensions shown 30 herein, (as for the purpose of obtaining devices for various standard capacities), the general proportions should be followed in this respect, that with larger inlet area, there should be larger sizes of passage Z and 35 larger diameters of outlet H. It is not necessary to use only a single inlet for either the auxiliary fluid or the oil. When the total inlet area of each is substantially increased, particularly to such an extent as to make 40 the construction awkward or to necessitate too great a distance between the inlets A⁶ and O⁶, then each inlet means may consist of a series, preferably annular, of inlets, as is indicated in Fig. 5. In this case, the best 45 operation will result from an increased length, as well as diameter, of the passage Z; and in any such case, each of the individual oil inlets O⁶ may be sufficiently small to alone obtain extremely fine nebulæ with- 50 out the positive assistance of the auxiliary fluid for that purpose; the latter, however, being preferably admitted eccentrically in such case, or so as not to interfere with the whirling action of the oil, such as would re- 55 sult from a supply axially of the passage Z.

I claim:

1. In a liquid nebulizer, the combination 60 with a support provided with means for receiving a plurality of pipe connections and with a recess adapted for the reception of a nebulizer plug, and having passages respectively communicating between said recess and pipe-receiving means; of a nebulizing plug secured in the recess in said support and dividing the recess into separate

chambers, said plug being provided with a short substantially unobstructed main passage having a relatively small concentric outlet at its end, and a plurality of eccentrically directed inlet means into said main passage, said inlet means being arranged to communicate with the respective chambers into which the recess in the support is divided by means of the nebulizing plug. 70

2. In a liquid nebulizer, the combination 75 with a support provided with means for receiving a plurality of pipe-connections and with a recess adapted for the reception of a nebulizer plug, and having passages communicating with said recess and pipe receiving means; of a nebulizer plug secured in the recess in said support and dividing the recess into separate chambers, said plug being provided with a short substantially unobstructed main passage having a relatively small concentric outlet at its end, and a plurality of eccentrically directed inlet means into said main passage, said inlet means being arranged to communicate with the respective chambers into which the recess in the support is divided by means of the nebulizer plug; a cooling fluid circulator 80 secured to said support; a supply pipe extending through the fluid circulator and secured in said support; and supporting 85 means for the other end of said pipe and secured to the fluid circulator. 90

3. In a nebulizing apparatus, the combination 100 with a support constructed with a recess to receive a nebulizing plug; of a nebulizing plug secured in said recess and dividing the same into two separate chambers, said support being constructed with passages communicating between said chambers and sources of supply; said nebulizing 105 plug being provided with a short substantially unobstructed main passage having a relatively small outlet at its end; and said plug being constructed with separate passages from the said respective chambers to 110 the main passage, which passages are disposed substantially eccentrically with respect to the main passage of the nebulizing plug. 110

4. A liquid nebulizer having a plug 115 structure provided with a short substantially unobstructed main passage having a relatively small concentric outlet passage at its end, and exterior screw threads, and unthreaded exterior portions of less diameter 120 than said threads and on opposite sides thereof, and separate eccentric inlet means extending from said unthreaded portions directly into said main passage. 120

5. A nebulizer of liquid having a plug 125 structure provided with a short substantially unobstructed main passage, having a relatively small concentric outlet at its end, and separate inlet means into said passage for the liquid to be nebulized and 130

for an auxiliary fluid, one of said inlet means being inclined substantially tangentially to the wall of said main passage, each of said inlet means comprising a series of 5 passages annularly arranged around said main passage, and one of the two annular series of passages being located between the other and said concentric outlet.

6. A liquid nebulizer having a plug 10 structure provided with a short substantially unobstructed main passage, having a relatively small outlet at its end; inlet means into said passage, for the liquid to be nebulized; and inlet means for 15 auxiliary fluid, which comprises a series of inlets into said passage arranged annularly around the passage, one of said inlet means being inclined substantially tangentially to the wall of the main passage.

20 7. A nebulizing plug constructed with a short, substantially unobstructed main passage having a relatively small end outlet passage to the exterior of the plug, in combination with a plug-support arranged with 25 the plug to have two separate chambers communicating with openings for supply pipes; said plug being constructed with separate supply passages from said respective chambers, which supply passages communicate with said main passage of the plug, one 30 of said supply passages being disposed eccentrically with respect to said main passage.

8. In an apparatus for liquid nebulizing, 35 a structure provided with a main passage, two series of supply passages for liquid fuel and an auxiliary fluid opening into the main passage, and a constricted outlet passage; said main passage being substantially cylindrical and hollow, and substantially unobstructed throughout its diameter and inside 40 wall surface; each series of supply passages being located in an annular series around the main passage, and the inlet openings of each 45 series, into the main passage, being directed into the side of the main passage and toward a portion of the wall of only one side of the main passage, and the inlet openings of the passages of one series, into the main passage, 50 being directed eccentrically relative to the main passage, thereby causing both fluids to be whirled in the main passage; and said outlet passage being located at the end of the main passage and concentric therewith.

55 9. In a nebulizing apparatus, the combination with a support having two separate passages for a liquid supply and an auxiliary fluid supply, of a nebulizing plug removably mounted in the support and provided 60 with supply passages communicating with the passages in the support, said plug having also a main passage and constricted outlet passage, the main passage being substantially cylindrical and hollow and sub-

stantially unobstructed throughout its diameter and inside wall surface, and the constricted outlet being located at the end of the main passage and concentric therewith; and the inlet opening of each of said supply passages in the plug, into the main passage, being directed into the side of the main passage and toward a portion of the wall of only one side of the main passage; the inlet opening of one of said supply passages in the plug, into the main passage, being directed eccentrically relative to the main passage and thereby causing the liquid to be whirled in the main passage. 65 70 75

10. In a liquid nebulizer, the combination with a support having recesses for pipe connections and a recess for a nebulizing plug, of a hollow nebulizing plug removably secured in the latter recess to form separate chambers in said recess, passages from said chambers to the interior of the plug, passages from the pipe connection recesses to said chambers, and supply pipes mounted in the pipe connection recesses. 80

11. In a liquid nebulizer, the combination with a support constructed with a recess in one face to receive a nebulizing plug, of a cooling fluid circulator secured to the support on its opposite face, a nebulizing plug removably secured in its recess in the support, and supply pipes extending through the fluid circulator and mounted in the support, said support being constructed with 90 passages communicating between the supply pipes and the recess for the nebulizing plug. 95

12. In a liquid nebulizer, the combination with a support constructed with a recess in one face to receive a nebulizing plug, of a cooling fluid circulator secured to the support on its opposite face, a nebulizing plug removably secured in its recess in the support, 100 and supply pipes extending through the fluid circulator and mounted in the support, said support being constructed with passages communicating between the supply pipes and the recess for the nebulizing plug; and a twin pipe structure secured to the fluid circulator and communicating with said supply pipes. 105 110

13. In a liquid nebulizer, the combination with a support constructed with a recess in one face to receive a nebulizing plug, of a cooling fluid circulator secured to the support on its opposite face, a nebulizing plug removably secured in its recess in the support, a packing collar secured over the end 115 of the fluid circulator, and supply pipes extending through the packing collar and fluid circulator and mounted in recesses in the support. 120

14. In a liquid nebulizer, the combination with a support constructed with a recess in one face to receive a nebulizing plug, of a cooling fluid circulator secured 125

to the support on its opposite face, a nebulizing plug removably secured in its recess in the support, a packing collar secured over the end of the fluid circulator, a twin pipe structure secured to said packing collar, and supply pipes mounted in recesses in the support, extending through the fluid circulator

and communicating with the respective passages in the twin pipe structure.
